CLAIM

We claim the ornamental design for a display screen or portion thereof with graphical user interface, as shown and described.

DESCRIPTION

FIG. 1 is a front view of a first embodiment of a display screen or portion thereof with graphical user interface showing our new design; and,

FIG. 2 is a front view of a second embodiment thereof. The broken lines in the figures depict environmental subject matter and form no part of the claimed design. The outermost broken line in the figures shows a display screen or portion thereof and forms no part of the claimed design.
